UNITED STATES PATENT OFFICE.

ALLEN L. DUNCAN, OF CHESTER, WEST VIRGINIA.

IRONING TABLE AND CABINET.

Application filed November 27, 1925. Serial No. 71,747.

The present invention relates to an improved ironing table and cabinet.

An object of the present invention is to provide a compact structure combining an ironing board which may be folded out of the way and a cabinet supporting the ironing board and which may house appurtenances, such as irons and the like for convenient access in the use of the device.

10 Another object of the invention is to provide a cabinet with a foldable ironing board which may be carried entirely by the cabinet both when folded and when set up, and which affords a substantial and rigid support for the ironing board when it is set up.

15 The invention also provides a cabinet with a table top for supporting clothes and the like which when not in use provides a neat and attractive article of furniture with enclosed sides and front and which may be placed against a wall in an out of the way position and which when set up provides a clothes support which is adjustable with the ironing board and admits of the swinging of 20 the same in an edgewise direction to receive articles of clothing over the end of the ironing board without removing the same from its supporting position upon the cabinet.

25 The above and various other objects and advantages of this invention will appear in, and be understood from, the following detailed description of the present preferred embodiment, the same being illustrated in the accompanying drawings, wherein like 30 parts are designated by similar numerals of reference throughout the several views, and wherein:

35 Fig. 1 is a perspective view of a combined ironing board and cabinet constructed according to the present invention and set up for use with the outer end of the ironing board swung free of its support for placing a garment over the ironing board.

40 Fig. 2 is a longitudinal vertical section taken through the same.

45 Fig. 3 is a rear side elevation of the device folded, showing the ironing board partly broken away.

50 Fig. 4 is a view similar to Fig. 3 with the ironing board folded and the door of the cabinet partly opened, and

55 Fig. 5 is a top plan view of the folded device with the cover removed.

Referring to the drawings the device comprises a cabinet having a front wall 10, side

walls 11 and a rear wall 12, the latter being arranged vertically between the side walls 11 and between the front and rear edges of the same. The cabinet is provided with a top 13 which extends between the side walls 11 and between the front wall 10 and the rear wall 12, providing a space in the rear of the cabinet which is open through the top thereof and through the rear of the cabinet. A bottom 14 is provided between the side walls 11 and the front wall 10 and rear wall 12, and an intermediate shelf or partition 15 may also be provided and arranged intermediate the top 13 and bottom 14.

60 The front wall 10 has a door 16 mounted on hinges 17 to permit access to the closed compartments of the cabinet in which various devices or articles may be stored for convenient access in ironing or in handling the clothes.

65 Pivotedly mounted on the top 13 of the cabinet is a socket comprising a board or plate 18 having a centrally located pivot pin 19 extending downwardly through the top 13 and connected thereto by a cotter pin 20 or the like for securing the socket upon the cabinet and permitting the free turning of 70 the socket thereon. The socket is also provided with a hood 21 of sheet metal or the like which is fitted about the forward and lateral edges of the plate 18 and which has its top spaced above the plate and preferably flared upwardly toward the rear edge of the plate where the socket is left open to receive the inner end of an ironing board 22. As 75 best seen from Figs. 3 and 5, the socket is relatively broad to snugly receive therein the inner end of the ironing board, and such inner end of the ironing board is preferably reduced, as at 23 to fit the socket.

80 The ironing board 22 may be of the usual form with a tapering outer end to receive articles of clothing thereover, and is provided across its under side and near its outer end with a pair of cleats 24 for engaging 85 against the opposite sides of a tongue 25 which projects upwardly from a cross piece 26 carried upon the upper ends of a pair of legs 27 providing a foldable support for the outer end of the ironing board. The 90 lower ends of the legs 27 are connected together by a lower cross piece 28 to the intermediate portion of which is connected by an upwardly acting pin 29 the outer section 95 of an upwardly folding brace.

The brace comprises the outer section 30 and an inner section 31 connected together by a downwardly acting hinge 32 which is operated by breaking upwardly the joint between the sections 30 and 31. The inner section 31 is connected to the back of the cabinet by an upwardly acting hinge 33 which admits of the upward swinging of the section 31 into engagement with the back 12 of the cabinet.

The cabinet may be supported upon legs 34 of suitable length to admit free access beneath the cabinet for sweeping the floor, and the rear edges of the side walls 11 of the cabinet are provided with inwardly extending vertical cleats or flanges 35 adapted to overlap the edges of the ironing board 22 when the latter is folded as shown in Figs. 4 and 5. A hook 36 is mounted on the rear wall 12 of the cabinet to engage in an eye 37 carried upon the outer section 30 of the brace to hold the latter in folded position as shown in Fig. 4.

A sliding top or table 38 is mounted on top of the cabinet and is of boxlike construction to house the hood 21, and is provided at its lower lateral edges with inturned flanges 39 adapted to engage in undercut grooves or recesses 40 in the opposite lateral edges of the plate 18. The plate 18 therefore holds the cover 38 on top of the cabinet and permits of the sliding of the top lengthwise of the cabinet into extended position as shown in Fig. 2 so that the full width of the top may be utilized in supporting clothes while substantially the full length of the ironing board may be used for ironing purposes.

As the pivoted socket on top of the cabinet is rotatable with the swinging of the board 22, the top 38 is also swung or turned upon the upper end of the cabinet as shown in Fig. 1, and is securely held to the cabinet in all positions of adjustment.

When the ironing board is set up as shown in Figs. 1 and 2, and it is desired to fold or collapse the same, it is only necessary to swing the ironing board either upwardly or laterally at its free end to disengage the cleats 24 from the tongue 25, when the ironing board 22 may be withdrawn from the pivoted socket. The brace sections 30 and 31 are folded upwardly and move the adjustable support inwardly toward the cabinet. The depth of the space within the rear of the cabinet is proportioned to receive the folded brace, the adjustable support and the ironing board therein behind the cleats 35. The adjustable brace and the leg structure 27 are secured in collapsed position by the hook 36 as shown in Fig. 4, and the ironing board 22 is slid downwardly between the cleats 35 and the leg structure 27 to close the rear of the cabinet and to connect all parts together in a compact structure.

The cabinet may now be pushed against a wall with the ironing board toward the wall, the cleats 24 extending but a negligible distance beyond the rear edges of the side walls 11 so that the device may be placed close to the wall.

In setting the device up the reverse operations take place for as soon as the ironing board 22 is drawn upwardly from the cleats the support may be pulled out of the cabinet after the brace has been released from the hook 36. As the brace breaks upwardly it is supported by its own weight and locked in extended position. The inner end 23 of the ironing board is merely slipped into the pivoted socket and the cleats engaged over the tongue 25.

It is of course understood that various changes and modifications may be made in the details of construction and design of the above specifically described embodiment of this invention without departing from the spirit thereof, such changes and modifications being restricted only by the scope of the following claims.

What is claimed is:

1. A combined ironing board and cabinet comprising a cabinet body, a socket mounted on the upper end of the body, an ironing board adapted to be fitted at one end in the socket, a movable support arranged to fit in the back of the cabinet, and a folding brace between the cabinet and the support adapted to fold into the back of the cabinet with the support and to be extended from the cabinet to brace the support beneath the other end of the ironing board.

2. A combined ironing board and cabinet comprising a cabinet body, said cabinet having an open back, a socket mounted on the upper end of the body, an ironing board adapted to removably fit at one end into said socket, a support for said ironing board, a folding brace connecting said support and cabinet, said support and brace being adapted to fit into the open portion of said cabinet back, and means for retaining said support and brace in said cabinet.

3. A combined ironing board and cabinet comprising a cabinet body, a socket pivotally mounted upon the upper end of the body, a cover carried upon the top of the cabinet body to house said socket and slidably connected thereto, an ironing board removably fitting at one end in the socket, and a foldable bracing structure in the back of the cabinet body adapted to be extended for supporting the outer end of the ironing board, said ironing board with its socket and said cover adapted to be swung laterally to disengage the ironing board from the bracing structure.

4. A combined ironing board and cabinet comprising a cabinet body having an open back, a socket pivotally mounted on the

upper end of the cabinet body, an ironing board removably fitting at one end into said socket, a vertical support for the other end of said ironing board, means for removably holding said ironing board on said support, a folding brace secured at one end to said cabinet and at the opposite end to said sup-

port, said ironing board, brace and support being adapted to fit into the open section of the cabinet, and means for locking said ironing board, brace and support in the open section of the cabinet. ¹⁰
